(57) **CLAIM**

We claim the ornamental design for a shrub rake, as shown and described.

DESCRIPTION

FIG. 1 is an isometric view of the shrub rake.

FIG. 2 is a front side view of the shrub rake.

FIG. 3 is a back side view of the shrub rake.

FIG. 4 is a top view side view of the shrub rake.

FIG. 5 is a bottom view of the shrub rake.

FIG. 6 is a left side enlarged view of the shrub rake; and,

FIG. 7 is a right side enlarged view of the shrub rake.

The broken line showing of the handle is included for the purpose of illustrating structure and forms no part of the claimed design.
